UNITED STATES PATENT OFFICE

144,879

DESIGN FOR AN AIRPLANE

Ozell Whitworth, Detroit, Mich.

Application September 25, 1944, Serial No. 115,456

Term of patent 14 years

(Cl. D71—1)

To all whom it may concern:

Be it known that I, Ozell Whitworth, a citizen of the United States, residing at the city of Detroit, in the county of Wayne and State of Michigan, have invented a new, original, and ornamental Design for an Airplane, of which the following is a specification, reference being had to the accompanying drawings, forming a part thereof.

In the drawings:

Figure 1 is a bottom perspective view of an airplane, showing my new design, the left gun turret

being here shown in lowered position and the right one being retracted and not visible.

Figure 2 is a top plan view of the airplane,

Figure 3 is a rear elevational view, and

Figure 4 is a side elevational view on a reduced scale, showing right and left ball gun turrets both in lowered position.

I claim:

The ornamental design for an airplane, as shown.

OZELL WHITWORTH.
